(57) **CLAIM**

The ornamental design for a two-in-one brush, as shown and described.

DESCRIPTION

FIG. 1 is a front perspective view of a two-in-one brush showing our new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a front perspective view thereof, showing the two-in-one brush in a separated state of use.

The broken lines depict portions of the two-in-one brush that form no part of the claimed design.
